By Monroe A. Smith

Atty. Attorney

UNITED STATES PATENT OFFICE.

WILLIAM A. LARNED, OF SUMMIT, NEW JERSEY, ASSIGNOR TO THE DAYTON STEEL RACQUET COMPANY, OF DAYTON, OHIO, A CORPORATION OF OHIO.

ELASTIC METAL STRINGING, AND THE METHOD OF MAKING THE SAME.

1,422,998.

Specification of Letters Patent. Patented July 18, 1922.

Application filed February 13, 1922. Serial No. 536,135.

To all whom it may concern:

Be it known that I, WILLIAM A. LARNED, a citizen of the United States, residing at Summit, in the county of Union and State of New Jersey, have invented certain new and useful Improvements in an Elastic Metal Stringing and the Methods of Making the Same, of which the following is a specification.

10 One of the principal objects of my invention is to provide for tennis rackets and other uses, an elastic metal-stringing to which the required degree of stiffness is imparted by my improved method. The stringing may 15 comprise one, two or more wires that are first wound to form a helix of a number of coils per inch, and thereafter stretched in the direction of the axis of the latter, to reduce the number of coils per inch to secure the 20 desired degree of stiffness, weight and elasticity required of the wire for the use to which it is put.

If the use be that of a stringing for a tennis racket, a wire of a large number of 25 coils per inch is too heavy. Accordingly, by stretching or extending it, the desired stiffness and weight of the wire can be obtained, without sacrificing the degree of elasticity the wire should have to adapt it for a tennis 30 racket string.

In the accompanying drawings, Figure 1 is a plan view of a portion of a tennis racket containing my wire stringing. Figure 2 is a side view of a single wire wound to form a 35 helix containing a large number of coils per inch. Figure 3 is a cross section taken through the same. Figure 4 is a side view of the same wire after it has been stretched to reduce the number of coils per inch. And 40 Figure 5 is a cross section taken through the same.

Throughout the specification and drawings, similar reference characters denote corresponding parts.

In the accompanying drawings, the numeral 1 designates a wire of any suitable material, which is first wound around a central core, or an imaginary cylinder, to form a helix of a large number of coils per inch, as shown in Figures 6 and 7. This wire is 50 then stretched by any suitable means, or when being inserted in the racket, to reduce the number of its coils per inch to provide the desired stiffness, weight and elasticity required for the use to which it is put.

In Figure 1 this wire, so coiled and stretched, is employed as the stringing in a tennis racket frame 2, where it will easily give or yield when extended under the impetus of the ball and thereafter readily return to its original form. When extended, the coiled strand will decrease in diameter to give to the stringing which it constitutes, the desired resiliency for use in a tennis racket or other structure.

Having described my invention, I claim:

1. An elastic metal-stringing comprising a wire which has first been wound to form a helix of a number of coils per inch, and thereafter stretched in the direction of the 75 axis of the latter, to reduce the number of its coils per inch to give the degree of stiffness, weight and elasticity required of it for the use to which it is put.

2. The method of making an elastic metal-stringing of a desired stiffness, weight and elasticity, which consists in first winding a wire to form a helix of a number of coils per inch, and thereafter extending said wire in the direction of its longitudinal axis, to reduce the number of its coils per inch to a point where the desired degree of stiffness, weight and elasticity is obtained.

In testimony whereof I have hereunto set my hand this 10th day of February, 1922.

WILLIAM A. LARNED.

Witness:

HOWARD S. SMITH.
